(57) **CLAIM**

The ornamental design for a stop block clamp attachment, as shown and described.

DESCRIPTION

FIG. 1 is a front isometric view of the stop block clamp attachment of the present invention.

FIG. 2 is a rear isometric view of the stop block clamp attachment of the present invention.

FIG. 3 is a front elevation view of the stop block clamp attachment of the present invention.

FIG. 4 is a rear elevation view of the stop block clamp attachment of the present invention.

FIG. 5 is a lateral elevation view of the stop block clamp attachment of the present invention.

FIG. 6 is the opposite lateral elevation view of the stop block clamp attachment of the present invention.

FIG. 7 is an end view of the stop block clamp attachment of the present invention.

FIG. 8 is the opposite end view of the stop block clamp attachment of the present invention.

FIG. 9 is an isometric view of the stop block clamp attachment of the present invention in use condition showing context. The broken lines showing a saw, saw table, clamp and material to be cut are included for the purpose of illustrating environmental structure only and form no part of the claimed design; and,

FIG. 10 is a close-up isometric view of the stop block clamp attachment of the present invention in use condition showing context. The broken lines showing a clamp are included for the purpose of illustrating environmental structure only and form no part of the claimed design.
